UNITED STATES PATENT OFFICE.

HARRY A. LEE, OF KANSAS CITY, MISSOURI.

JOURNAL TRUING OR TURNING TOOL.

1,411,441.

Specification of Letters Patent.

Patented Apr. 4, 1922.

Application filed January 31, 1921. Serial No. 441,132.

To all whom it may concern:

Be it known that I, HARRY A. LEE, a citizen of the United States, and resident of Kansas City, county of Jackson, State of Missouri, have invented a certain new and useful Improvement in Journal Truing or Turning Tools, of which the following is a complete specification.

This invention relates to improvements in journal turning or truing tools, and has for its object to produce a tool of this character which may be readily and easily applied in position on the crank shaft of a motor car without taking down said shaft.

Another object is to produce a tool of this character which may be operated by hand or which may be used in connection with a lathe or other source of power.

A still further object is to produce a tool of this character of such form and proportion that adjustment of the cutting element or knife of the tool to accommodate shafts or the like of different diameter shall automatically effect such lateral adjustment of the cutter as shall insure its position in a plane perpendicular to the face of the stationary jaw, which extends diametrically through the shaft or object to be operated upon and thereby insure accurate truing or turning operations regardless of the diameter of the shaft or other object.

Another object is to produce a tool having a handle of such character that it will automatically break in the event the operator attempts to turn it in the wrong direction in performing the truing or turning operation.

With the objects named in view the invention consists in certain novel and useful features of construction and organization of parts as hereinafter described and claimed; and in order that it may be fully understood, reference is to be had to the accompanying drawing, in which:

Figure 1 is a side view of the tool partly broken away to more clearly illustrate the means for feeding the cutter into contact with the shaft being turned.

Figure 2 is an edge view of the tool.

Figure 3 is a section on the line III—III of Figure 1.

Figure 4 is a perspective view of a clamping plate forming a part of the invention.

In the said drawing, where like reference characters identify corresponding parts in all of the figures, 1 is a grip handle pro-

vided with a break joint portion 2, in order that pressure, as hereinafter explained, may be applied on the handle only in the direction indicated by the arrow, Figure 1, said handle bearing at its upper end an abutment arm 3, which is secured at right angles to a shank portion 4 by means of a bolt 5. The opposite end of the shank portion is formed with an extension 6, standing at an angle of twenty seven and one half ($27\frac{1}{2}$) degrees to the shank portion. Projecting from the upper end of the extension and at a right angle thereto is a jaw 7, which is provided with a hard metal wearing plate 8 secured in place by screw bolts 9.

The upper end of the abutment arm 3 is provided with an opening accommodating an adjusting screw 10, provided with a grip portion 11 at one side of plate 9 and with an abutment collar 12 at the opposite side of said plate, these parts 11 and 12 preventing endwise movement of the screw when turned as well as offering a fixed bearing for such screw. The screw 10 extends parallel with shank 4 and engages a threaded bore 13 formed on a sliding sleeve 14 mounted on the shank, said sleeve embodying a removable plate 15 in order that the sleeve may be secured in or removed from operative position.

The upper end of the sliding sleeve 14 is provided with an L-shaped recess 16 to accommodate a cutter member 17, held immovably in position by means of a clamping plate 18, which is held in position by means of a pair of screw bolts 19, it being noted that said bolts engage threaded openings in the sliding sleeve 14, as shown. It will also be noted that the clamping plate 18 is provided between the screw bolts 19 with a V-shaped projection or lug 20, having a threaded socket 21 for engagement by a thumb screw 22, said screw extending through a guard 23 and clamping the same against the lower face of said lug so that it shall stand approximately parallel to the extension 6 of the shank, and be employed, if necessary, to aid in maintaining the tool in operative position upon a shaft 24 in the initial part of the turning or truing operation of the tool as there is no tendency for the tool to be forced out of engagement with the shaft when turned in the proper direction.

It will be noted, by reference to Figure 1, that the cutter will always come in contact with the shaft being turned, in the line of

a perpendicular through the axis A of the shaft, dropped from the plane of the face of the wear plate 8, and this relative position of the parts is due to the fact that the shank 5 portion 4 is set at an angle of twenty seven and one half ($27\frac{1}{2}$) degrees to its extension 6. The drawing shows operative application of the tool to a shaft on one and one-quarter (1 $\frac{1}{4}$) inches in full lines and to a 10 shaft of two (2) inches in dotted lines, and in both cases it will be noted that the edge of the cutter stands in the relative position above-mentioned with respect to the axis of the shaft. The adjustment of the cutter is 15 effected by rotation of the screw 10, as this operation imparts sliding movement in one direction or the other to the sleeve 14 upon shank 4, and due to the angle of the latter will draw the cutting edge a distance down- 20 ward parallel to the face of extension 6 just twice the distance the cutting edge is moved away or at right angles to said extension, thus maintaining at all times the relative positions above-mentioned.

25 It is believed that no recapitulation of the operation of the tool is necessary, except to state, that the revolving of the shaft or tool must be in such direction that the force applied on handle 1 will always be in the direction indicated by the arrow, Figure 1, the break joint 2 being provided in order to automatically guard against accidental turning of the members in the wrong direction. The use of this tool produces a perfectly 30 smooth and accurately rounded surface on the shaft or other object, and should the surface to be turned or rounded be somewhat wider than the cutting member, the tool or shaft may be relatively shifted while the 35 truing operation is in progress. It will also be apparent that a cutter a little shorter or a little longer than the clamping plate 18 may be successfully employed, when the surface to be turned varies within a limited 40 degree in width.

45 From the above description it will be apparent that I have produced a tool of the character described, which possesses all of the features pointed out as desirable, and 50 while I have described and illustrated the preferred embodiment of the same, I reserve the right to make all changes properly falling within the spirit and scope of the appended claims.

55 I claim:

50 1. A tool of the character described, comprising a shank having an extension, a jaw projecting from said extension for contact with a shaft, a cutter for engagement with the shaft at the opposite side thereof from and in a plane extending perpendicularly to the said jaw through the axis of the shaft, and means for effecting relative adjustment 100 between said cutter and extension and jaw

at an angle of substantially twenty seven 65 and one half ($27\frac{1}{2}$) degrees with respect to a plane intersecting the axis of the shaft and perpendicular to the face of the jaw at the point where the latter contacts with said shaft. 70

2. A tool of the character described, comprising a shank having an extension, a jaw projecting from said extension for contact with a shaft, a cutter for engagement with the shaft at the opposite side thereof from and in a plane extending perpendicularly to the said jaw through the axis of the shaft, and means for adjusting said cutter on said shank toward and from said jaw at an angle of substantially twenty seven and one half 75 ($27\frac{1}{2}$) degrees with respect to said extension. 80

3. A tool of the character described, comprising a shank having an extension, a jaw projecting from said extension for contact with a shaft, a cutter for engagement with the shaft at the opposite side thereof from and in a plane extending perpendicularly to the said jaw through the axis of the shaft, and screw-actuated means for adjusting the cutter on said shank toward and from said 90 jaw at an angle of substantially twenty seven and one half ($27\frac{1}{2}$) degrees with respect to said extension. 95

4. A tool of the character described, comprising a shank having an extension, a jaw projecting from said extension for contact with a shaft, a sleeve mounted for sliding on the shank toward and from said jaw at an angle of substantially twenty seven and one half ($27\frac{1}{2}$) degrees with respect to said 100 extension, and a cutter rigidly carried by said sleeve with its cutting edge extending transversely of and parallel with the adjacent face of the said jaw.

5. A tool of the character described, comprising a shank having an extension, a jaw projecting from said extension for contact with a shaft, a sleeve mounted on said shank, screw-actuated means for adjusting said sleeve upon the shank toward and from said 110 jaw at an angle of substantially twenty seven and one half ($27\frac{1}{2}$) degrees with respect to said extension, and a cutter rigidly carried by said sleeve and extending parallel with the adjacent face and transversely 115 of said jaw.

6. A tool of the character described, comprising a shank having an extension at one end and a handle at the other, the handle being pivoted for swinging movement in 120 one direction from a predetermined position and incapable of swinging in the opposite direction from said position, a jaw projecting from said extension, a sleeve mounted adjustable on said shank toward and from said jaw at an angle of substantially twenty seven and one half ($27\frac{1}{2}$) degrees with respect to said extension, and a cutter rigidly 125

carried by said sleeve and extending parallel with the adjacent face and transversely of said jaw.

7. A tool of the character described, comprising a shank provided at its opposite ends with an extension and a handle extending in parallel relation but in a different plane, a jaw projecting from said extension at right angles thereto, a sleeve adjustable 10 on said shank toward and from said extension at an angle of substantially twenty seven and one half ($27\frac{1}{2}$) degrees with respect thereto, and a cutter carried by said sleeve and extending parallel with the adjacent face and transversely of said jaw.
8. A tool of the character described, comprising a shank, provided at one end with an extension extending at an angle to the shank, a jaw projecting from said extension 20 at right angles thereto, a handle extending parallel with said extension and detachably secured to the opposite end of the shank from said extension, a sectional cutter slid- 25 ingly mounted on said shank and provided with a threaded bore, a screw journaled in

said handle and engaging said threaded bore of said sleeve, and a cutter rigidly carried by said sleeve and extending parallel with the adjacent face and transversely of said jaw.

30

9. A tool of the character described, comprising a shank having an extension, a jaw projecting from said extension for contact with a shaft, a cutter for engagement with the shaft at the opposite side thereof from 35 and in a plane extending perpendicularly to the said jaw axially of the shaft, means for adjusting said sleeve on said shank toward and from said jaw at an angle of substantially twenty seven and one half ($27\frac{1}{2}$) de- 40 grees with respect to said extension, and a guard secured to said sleeve and projecting therefrom substantially parallel with said extension, for engagement with the opposite side of said shaft from said extension to 45 hold the shaft between the said jaw and cutter.

In witness whereof I hereunto affix my signature.

HARRY A. LEE.
